EX

OR D 12,958

DESIGN FOR WALL-PAPER.

Design No. 12,958, dated June 6, 1882.

UNITED STATES PATENT OFFICE.

EDUARD LEISSNER, OF NEW YORK, N. Y.

DESIGN FOR WALL-PAPER.

SPECIFICATION forming part of Design No. 12,958, dated June 6, 1882.

Application filed April 21, 1882. Term of patent 3½ years.

To all whom it may concern:

Be it known that I, EDUARD LEISSNER, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper bearing my new design.

A is a band running along the upper border of the design and ornamented with a row of bead-like figures along each edge, between which are set figures *a*, composed of concentric beaded circles and alternating with looped and hanging rows of beads along the band A.

The stripe H contains the figure G in the center of the design. This figure consists of a scalloped circular figure, having on each side thereof a bud-like figure, *d*, and having projecting from it the stem *i*, bearing leaves on either side and a tulip-like flower on its top. The figure *f* resembles a bush or plant, with regular leaves and large tulip-like flowers, overtopped by a tulip-like flower, *h*, supported on a central stem.

The figure D is composed of a circular figure, *e*, from which projects a long tulip-like flower, *g*. The figure E resembles a plant, having a central stem, *m*, from which project a number of branches or stems, each bearing a flower at its end, circular and tulip-shaped flowers alternating, the flower *n* at the end of one stem being composed of a series of overlapping nearly-circular leaves. Around these figures D, E, G, and *f* runs a beaded band, conforming substantially to the shape of the figures D and G,

and the parts of these various figures are all made up of series of small bead-like figures placed close together, so that the whole effect is as if they were formed of closely-strung rows of beads.

The band B, below the stripe H, is bordered on either edge by beaded lines, and contains an ornamentation of a series of beaded circles, *b*, with beaded arches between them, which alternately touch the top and the bottom of the beaded lines, between which the band B is contained.

I claim—

1. The design for wall-paper, consisting of the band A, substantially as shown.
2. The design for wall-paper, consisting of the figure D, substantially as shown.
3. The design for wall-paper, consisting of the figure *f*, substantially as shown.
4. The design for wall-paper, consisting of the figure G, substantially as shown.
5. The design for wall-paper, consisting of the figure E, substantially as shown.
6. The design for wall-paper, consisting of the figures E, G, and *f*, substantially as shown.
7. The design for wall-paper, consisting of the stripe H, containing figures D, *e*, *g*, E, *m*, *n*, G, *d*, *i*, *f*, and *h*, substantially as shown.
8. The design for wall-paper, consisting of the band B, containing figure *b*, substantially as shown.
9. The design for wall-paper, consisting of the band A, containing figure *a*, stripe H, containing figures D E G f e g m n d i h, and band B, containing figure *b*, substantially as shown.

EDUARD LEISSNER.
